UNITED STATES PATENT OFFICE.

CARL EMIL PEDERSEN, OF ÖSTRE AKER, NEAR CHRISTIANIA, NORWAY.

COMBUSTION DEVICE FOR STEAM-BOILERS AND THE LIKE.

1,257,108.

Specification of Letters Patent. Patented Feb. 19, 1918.

Application filed December 31, 1915. Serial No. 69,510.

To all whom it may concern:

Be it known that I, CARL EMIL PEDERSEN, a subject of the King of Norway, residing at Östre Aker, near Christiania, Norway, 5 have invented certain new and useful Improvements in Combustion Devices for Steam-Boilers and the like; and I do hereby declare the following to be a full, clear, and exact description of the invention, such as 10 will enable others skilled in the art to which it appertains to make and use the same, reference being had to the accompanying drawings, and to letters or figures of reference marked thereon, which form a part of this 15 specification.

My present invention relates to coal burners or combustion devices for steam boilers, and the object of my invention is to provide a combustion device into which the coal 20 pieces are fed continually from above and evaporize before they reach the bottom of the combustion chamber. Each combustion chamber forms an independent unit and is connected with the fire space of the boiler by 25 means of a tube or mouth piece. A convenient number of such combustion chambers may be provided for each boiler. The present coal burner differs from the well known coal dust burners, where coal dust is injected 30 together with air in the heating space of the boiler in that the coal used is not in the form of dust or powder but only granulated to a size of ordinary nuts or small walnuts. Nor 35 are these coal pieces injected into the heating space of the boiler but are merely dropped into the combustion chamber, where they evaporize completely owing to the great heat in the said chamber.

On the drawings:

40 Figure 1 is a vertical sectional view of a combustion chamber and a boiler.

Fig. 2 is a plan sectional view of the boiler and several combustion chambers, while Fig. 3 is a section through a boiler 45 house showing the arrangement of the combustion chamber according to the invention.

Referring now to Figs. 1 and 2 A is a combustion chamber which may consist of a plate iron casing with an interior lining of 50 refractory material. Each casing has a refractory mouth piece B, which projects into the boiler C through an opening in the wall of the same. The coal is fed from the hopper D by means of a suitable feeding device E and is dropped into the combustion

space F. The temperature in this space being extremely high owing to the combustion, which may be aided by means of pressure air draft from pipes H, the coal pieces will be completely evaporized and partly combusted during their fall toward the grate G, and the combustion products as well as the evaporized non combusted coal gas owing to the air pressure will be blown through the mouth piece B into the boiler C. In 60 order to avoid irregularities in the heating of the furnace a heat absorbing body I may be placed in the boiler in front of the mouth pieces B, so that it is heated by the flame from the said mouth piece. This heat absorbing body may consist of stones and gravel or other convenient substances. In 65 order to allow for repair of the combustion chambers the same are provided with wheels K running on rails L, so that they may 70 easily be taken away and changed.

In the embodiment above described the combustion chambers are connected to the boiler, at one side of the same, and this arrangement is the most convenient when an 80 old boiler is to be provided with the present coal burners. When however a new boiler shall be equipped with the present arrangement, this may be done according to Fig. 3 by placing the combustion chambers A at 85 one end of the boiler.

Claims:

1. In a device of the character described, the combination with a boiler, of a combustion chamber adjacent thereto, an elongated 90 mouthpiece at the top of said combustion chamber and projecting therefrom into the heating space of the boiler, and means for feeding fuel into the top of said combustion chamber transversely of the path of the 95 flame and gases through said mouth-piece, whereby said fuel will fall the length of said combustion chamber and be subject to the action of an air current in said combustion chamber.

2. In a device of the character described, the combination with a boiler, of an elongated combustion chamber independent thereof and adjacent thereto, a mouthpiece formed integrally with the top of said combustion chamber and projecting therefrom into the heating space of the boiler, means for feeding fuel into the top of said combustion chamber transversely of the path of the 105 flame and gases through said mouthpiece, 110

whereby said fuel will fall the length of said combustion chamber, and means for admitting compressed air to said combustion chamber substantially in line with said mouthpiece and in position to assist in consuming the fuel fed to the combustion chamber.

In testimony that I claim the foregoing as my invention, I have signed my name in presence of two subscribing witnesses.

CARL EMIL PEDERSEN.

Witnesses:

M. E. GUTTORMSEN,

THS. HERZ.
